UNITED STATES PATENT OFFICE.

HARRY A. DOUGLAS, OF BRONSON, MICHIGAN.

CIRCUIT-CONTINUING DEVICE.

1,347,737.

Specification of Letters Patent. Patented July 27, 1920.

Application filed August 15, 1918. Serial No. 250,024.

To all whom it may concern:

Be it known that I, HARRY A. DOUGLAS, citizen of the United States, residing at Bronson, in the county of Branch and State 5 of Michigan, have invented a certain new and useful Improvement in Circuit-Continuing Devices, of which the following is a full, clear, concise, and exact description.

My invention relates to circuit continuing devices and has for its general object the provision of an improved assembly of component parts of such a device. My invention is of particular service in conjunction with an incandescent lamp structure as 10 thereby I am enabled to readily demount the lamp bulb and replace it by a circuit extending plug upon one end of a flexible cord whose other end carries a socket with which the lamp may be connected. Such a lamp is 15 of especial utility in connection with automobiles, the device of my invention enabling me so to mount an incandescent lamp upon the dash board of an automobile that it may readily be relocated upon the end 20 of the flexible cord which is sufficiently long to enable the lamp to be moved throughout the automobile for the purpose of inspection, the lamp then serving as a so-called "trouble" lamp.

30 In carrying out my invention I employ a main socket which, in the case of an automobile cowl lamp, would be mounted on the dash board of the automobile, a supplemental socket at the forward end of the main socket and in separable engagement therewith, a contact carrier, such as the base of the lamp, in the supplemental socket, and a contact carrier in the main socket having a contact or contacts for engaging a contact 35 or contacts upon the carrier in the supplemental socket. In an incandescent lamp structure the contact carrier in the main socket has a forwardly spring pressed contact for engaging the corresponding contact upon the lamp base and, by such engagement, serving to maintain the lamp and supplemental socket together and also serving to maintain the supplemental socket and the main socket together.

40 In the preferred form of the invention the two sockets are in bayonet projection and channel connection and the contact carrier in the supplemental socket is in bayonet projection and channel engagement with 45 this socket. Where the incandescent lamp bulb is housed within a hood or cowl the

supplemental socket is desirably provided with a skirt that supports the cowl. When the circuit extending cord is to be used the supplemental socket is uncoupled from the 50 main socket and is coupled with the socket at the outer end of the cord, the inner plug end of the cord being coupled with the forward end of the main socket, the lamp at the outer end of the cord being supplied 55 with current through the circuit extending cord.

The invention has other features and characteristics and will be fully explained by reference to the accompanying drawings 60 showing the preferred embodiment thereof and in which Figure 1 is a longitudinal sectional view of a cowl lamp made in accordance with the invention; Fig. 2 is a view, mainly in longitudinal section, illustrating 65 a circuit extending cord; Fig. 3 is a view illustrating the combination of structures illustrated in Figs. 1 and 2, the supplemental socket being replaced by the plug on the inner end of the circuit extending cord, the 70 removed supplemental socket and the lamp 75 therein together with the cowl about the lamp being now coupled with the outer socket end of the circuit extending cord; Fig. 4 is a view on line 4—4 of Fig. 1; Fig. 80 5 illustrates the parts shown in Fig. 4 in separated relation; Fig. 6 is a view on line 6—6 of Fig. 4, on a larger scale; Fig. 7 is a view on line 7—7 of Fig. 4, on a larger 85 scale; Fig. 8 is a view on line 8—8 of Fig. 90 4, on a larger scale; and Figs. 9 and 10 are views showing modifications of parts.

Like parts are indicated by similar characters of reference throughout the different figures.

95 The main socket or shell 1 is supported within a ferrule 2 having a flange 3 which is screwed to the dash board or other mounting 4. This main socket contains a contact carrier 5, and as the structure illustrated 100 is a so-called two pole structure but to which the invention is not to be limited, this contact carrier supports two spring contacts comprising contacting plungers 6 and 7 which are respectively forwardly pressed 105 by coiled springs 8 and 9. The plunger contact 7 and the coiled spring 9 operate in the bore of a terminal conductor 10 to which a circuit conductor 11 is secured. The other circuit conductor 12 is secured to a terminal 110 conductor 13 having a bore in its forward end. A plunger contact 14 operates in this

bore and is pressed forwardly by a coiled spring 15. A switching metallic contact 16 is mounted in the insulating bar 17 that is a carrier for the contact 16 and which bar 5 passes transversely through the shell 1 and is movable laterally of such shell. The spring 8 and the contact 6 are operable in a current conducting spring barrel 18 which is alined with the plunger contact 14. When 10 the switching contact 16 is placed in alinement with the plunger contact 14 and the spring barrel 18, the plunger contact 6 is electrically connected with the circuit conductor 12 whereby any circuit continuing 15 device that is connected with the forward ends of the contacts 6 and 7 is included in circuit. When the switching contact 16 is moved out of alinement with the elements 14 and 18 the circuit is opened. The forward 20 end of the main socket 1 has bayonet channels formed therein, these bayonet channels preferably being in the nature of bayonet slots 19 extending through the side of the socket 1. A supplemental socket 20 surrounds 25 the forward end of the main socket and has inwardly extending bayonet projections 21 for engagement with the bayonet seats afforded by said bayonet slots or channels to couple both sockets separably. The 30 supplemental socket, in surrounding the main socket, conceals the bayonet slots 19 to improve the appearance of the structure and the bayonet channels 19, by being in the form of slots, permit the coupling of a circuit 35 extending plug with and within the main socket 1 when the supplemental socket 20 is removed. An incandescent lamp bulb 22 has its base supplied with bayonet projections 23 which are insertable within the 40 bayonet channels or slots 24 formed in the supplemental shell 20 in order separably to couple the lamp bulb with said supplemental socket. The base of this lamp bulb constitutes a contact carrier which supports 45 the contacts 25 and 26 which are connected with the terminals of the lamp bulb filament. These contacts 25 and 26 are engaged by the forwardly spring pressed contacts 6 and 7 when the main and supplemental 50 sockets have been assembled and when the lamp bulb is assembled with the supplemental socket. These contacts 6, 7, pressing forwardly upon the contacts upon the lamp bulb base, maintain all of said bayonet projections 21 and 23 in engagement with their 55 seats in the corresponding bayonet channels 19 and 24. When the aforesaid switching contact 16 is alined with the contacts 14 and 18 to be engaged thereby the incandescent 60 lamp bulb is in circuit and when this contact 16 is out of such alinement the circuit of such lamp bulb is open.

Where a cowl or hood is to be provided for the lamp bulb the socket 20 desirably 65 has a cylindrical skirt 27 thereon upon

which the cylindrical cowl 28 may be disposed and on which skirt said cowl may be turned to adjust the location of the light emitting opening 28¹ formed in the cowl.

When the lamp bulb is to be placed upon 70 the end of a circuit extending cord in order that it may be shifted about to furnish light upon parts to be inspected, it is not necessary to remove the cowl and thereafter to remove the lamp bulb since the entire supplemental socket carrying the lamp bulb and cowl may be uncoupled from the main socket and thereafter connected with the forward end of a flexible circuit extending cord 29 whose rear end is connected with 75 the main socket. When the inspection has been concluded the relocation of the supplemental socket upon the main socket may readily be effected. The adjustment of the lamp bulb from main socket to cord and 80 vice versa is thus simply and easily effected without danger of breaking or impairing the bulb and without the necessity of manipulating a large number of parts in order to shift the bulb. 85

The circuit extending cord 29 has a contact structure upon its rear end which is in the form of a contact carrying plug 30 having conductor terminals 31, 32 connected with the strands 33, 34 of the cord. This 90 plug carries bayonet projections 35 which are receivable in the bayonet channels or slots 19 when the supplemental socket 20 is removed, the forwardly pressed spring contacts 6 and 7 engaging the contacts 31, 32 95 when the plug 30 is assembled with the main socket 1. The other end of the circuit extending cord 29 is provided with a contact structure which preferably includes a socket 36 which holds a contact carrier 37 that 100 supports terminals 38, 39 that are connected with the strands of the cord. The forward ends of the terminals 38 and 39 are formed with bores in which coiled springs 40, 41 are disposed and in which the plunger contacts 42 and 43 operate, these contacts being forwardly pressed by said springs. The socket 36 has bayonet channels or slots 44 formed therein at its forward end to receive the bayonet projections 21 on the supplemental socket 20 in order separably to couple this supplemental socket with the cord socket 36. When so coupled the springs 40 and 41 press the contacts 42 and 43 against the contacts 25 and 26 upon the lamp bulb 110 base. The spring pressed contacts 42 and 43 not only serve to maintain the bayonet projections 23 in engagement with the bayonet channels 24 but by reason of the engagement so maintained the bayonet projections 21 are maintained in engagement with the bayonet channels 44. In this assembly the socket 36, in its relation to the supplemental socket 20, is a main socket. 115

The socket that contains the lamp bulb 120

base or other contact carrier may be variously formed, a modification of the structure shown in Fig. 5 being illustrated in Fig. 9. In the construction shown in this 5 latter figure the portion that contains the bayonet slots 24 is a returned portion 20 of the socket, this returned portion being free of the socket at its rear end instead of being rigidly connected with the socket as in the 10 construction of Fig. 5. The modified contact carrier 30 shown in Fig. 10 has a different form of bayonet pins 35 than that elsewhere shown.

The advantages and utility of the outfit 15 of my invention will be readily understood by those skilled in the art and while I have herein shown and particularly described the preferred form of the invention I do not wish to be limited thereto nor, in all instances, do I wish to be limited to the combination of my improved lamp structure 20 with the circuit extending cord structure. It will be understood that changes may readily be made in the construction shown 25 without departing from the spirit of my invention, but having thus described my invention I claim as new and desire to secure by Letters Patent the following:—

1. An incandescent electric lamp structure 30 including a main socket; a supplemental socket at the forward end of the main socket and in separable bayonet projection and channel engagement therewith; an incandescent lamp bulb whose base is in separable bayonet projection and channel engagement with the supplemental socket; and a contact carrier in the main socket having a spring contact pressing forwardly upon a contact upon the lamp bulb base to maintain all of said bayonet projections in engagement with their seats in the bayonet channels, in combination with a circuit extending cord having a plug at one end which is insertable within the forward end of the 40 main socket and carries a contact engageable

with a complementary contact upon the carrier in the main socket, said cord having a socket at its other end formed to have separable bayonet projection and channel engagement with the supplemental socket, this 50 socket upon the cord having a contact carrier provided with a spring contact pressing forwardly and adapted to engage a complementary contact upon the lamp base that is within the supplemental socket. 55

2. An incandescent electric lamp structure including a main socket adapted to receive a circuit extending plug within its forward end; a supplemental socket surrounding the forward end of the main socket and in separable bayonet projection and channel engagement therewith; an incandescent lamp bulb whose base is in separable bayonet projection and channel engagement with the supplemental socket; and a contact carrier in the main socket having a spring contact pressing forwardly upon a contact upon the lamp bulb base to maintain all of said bayonet projections in engagement with their seats in the bayonet channels, in combination with a circuit extending cord having a plug at one end which is insertable within the forward end of the main socket and carries a contact engageable with a complementary contact upon the contact 75 carrier in the main socket, said cord having a socket at its other end receivable in the supplemental socket and formed to have separable bayonet projection and channel engagement therewith, this socket upon the 80 cord having a contact carrier provided with a spring contact pressing forwardly and adapted to engage a complementary contact upon the lamp base that is within the supplemental socket. 85

In witness whereof, I hereunto subscribe my name this twelfth day of August, A. D. 1918.

HARRY A. DOUGLAS.
